FOLDING LITTER

Samuel G. Thomson, Flushing, N. Y., assignor to
Zimmer-Thomson Corporation, Flushing, N. Y.

Application May 9, 1941, Serial No. 392,766

13 Claims. (Cl. 5—82)

This invention relates to litters for transporting sick or injured persons and has special reference to a folding litter especially adapted for military uses in transporting wounded persons.

It is understood that whenever the term "metal" is used various materials may be substituted as full equivalents and among such materials are plastics, ply-wood and any kind of laminated or built up compositions. It will be noted that aluminum is the metal often used in such constructions as the present device and the use of other materials, such as those mentioned, tends to conserve aluminum for more important military uses. Obviously the cross-sections of the parts may be varied in thickness and width according to the exact stress and strain calculations necessitated by the materials used, and in order to save weight at places where such weight can be saved without impairing the strength required for the part.

One important object of the invention is to provide a novel construction of folding litter wherein the major metal parts such as the sidebar saddles, the legs and the stretcher bars may be made from rolled or extruded metal, plastics or other material thus eliminating the use of castings for such parts.

A second important object of the invention is to provide an improved leg construction for such a litter wherein the leg is made from strap material bent and curved to proper shape to provide proper spacing for one end of a stretcher bar section.

A third important object of the invention is to provide such a litter with a leg and stretcher bar arrangement of such character that the stretcher bars may be made of straight strap material.

A fourth important object of the invention is to provide an improved connection between the adjacent ends of each pair of stretcher bar sections in which the limitation of movement of these parts, necessary when the litter is expanded, is effected without the foundation or use of lugs or offsets on the stretcher bar sections.

A fifth important object of the invention is to provide a litter of this character wherein broken or injured parts may be readily replaced.

A sixth important object of the invention is to provide a folding litter wherein the leg and stretcher bar arrangement is such as to present no interference to the closing of the side-bars or poles on one another, the presence of the fabric connecting these side-bars or poles being all that prevents actual contact between them when col-

lapsed thus occupying a minimum of cross-sectional space.

With the above and other objects in view, as will be further set forth, the invention consists in general of certain novel details of construction and combinations of parts hereinafter fully described, illustrated in the accompanying drawings and particularly pointed out in the appended claims.

10 In the accompanying drawings like characters of reference indicate like parts in the several views, and:

Figure 1 is a bottom plan view of one end of a litter constructed in accordance with this invention and showing the litter expanded in full lines and in substantially collapsed position in dotted lines.

Figure 2 is a side elevation of the parts shown in Figure 1, similarly disclosing the expanded and collapsed positions.

Figure 3 is an enlarged perspective view showing one form of strap leg and the connection of a stretcher bar section thereto.

Figure 4 is a transverse detail section on the line 4—4 of Figure 1 and showing one form of pivotal joint for connecting the legs and stretcher bar sections.

Figure 4a is a perspective view of a bushing used in connection with the joint shown in Figure 4.

Figure 20 is a perspective view showing a bushing and washer used in Figure 19 in disassembled relation.

Figure 21 is a view similar to Figure 19 but showing a modification of the joint.

Figure 22 is a fragmentary plan view of a second modification of the stretcher bar joint.

Figure 23 is a section on the line 23-23 of Figure 22.

Figure 24 is a fragmentary plan view of a third modification of the stretcher bar joint.

Figure 25 is a section on the line 25-25 of Figure 24.

Figure 26 is a bottom plan view to reduced scale of a complete litter constructed in accordance with this invention.

In the folding litter as here shown there is provided a pair of side bars or poles 10 generally illustrated as circular in cross-section although the middle portions of these bars may be rectangular as shown at 10a in Figure 5. These poles are provided with the usual handles 11 and carry the usual fabric litter bottom 12. In the majority of the views of the drawings the fabric is omitted the better to show the working parts whereby the litter may be collapsed and expanded. Each of these poles is provided with a pair of saddles one form of which for round poles is indicated at 13 while another form for round poles is shown at 13a (Fig. 6) and a form for square poles at 13b (Fig. 5). Under each of the saddles is a leg indicated in general at 14 and the legs of the poles are connected by stretcher bar arrangements indicated in general at 15.

Referring now to the saddle 13 as shown in Figures 3 and 4 this member is preferably formed as an extruded bar having an arcuate pole seat 16 at its upper side and a shallow leg channel 17 in its lower face. In Figures 6, 11 and 12 the saddle 13a has the usual pole seat 18 and a cross

channel or groove 19 in its lower face. In Figure 5 the channel 20 of the upper face is shaped to fit the square pole 10a and a channel 21 similar to the channel 17 is provided.

5 The leg 14 of Figures 2 and 3 is formed from a strip or bar of metal of uniform width and thickness such as may be produced by extrusion or rolling. This bar has a straight upper portion 22 which fits into the channel 17, the thickness of the bar being such as to cause it to project somewhat below the walls of the channel. Extending downwardly from one end of the portion 22 is a depending portion 23 which merges by a curve 24 into an arcuate leg bottom or ground engaging portion 25 at one end thereof. The other end of the portion 25 merges into an arcuate portion 26 which in turn merges into an upright portion 27. From the top of the portion 27 extends a straight portion 28 parallel to the portion 22 and provided with an upturned terminal portion 29 engaging the portion 22 adjacent the portion 23. The portions 23 and 27 diverge from their upper ends downwardly. The portions 22 and 28 are provided with suitable openings for a bolt 30 which passes through the pole 10 and through these openings. A nut 31 on the lower end of the bolt 30 serves to hold the pole, saddle and leg firmly and immovably together. It is to be noted that a wide laterally disposed space 32 is provided between the portions 22 and 28 and the purpose of this space will be presently explained.

In the form of the leg shown in Figures 7 to 13 and 15 the structure is similarly made from strip or bar metal. In Figure 7 the bar is formed with a straight upper portion 33 corresponding to the portion 22 and from one end of the portion 33 the bar extends in a circular arc 34 the lower part of which engages the ground. The arc 34 merges into an arcuate portion 35 which in turn merges into a straight portion 36 parallel to the portion 33 and terminating against the portion 34. The portions 33 and 36, being spaced, provide the wide space 32 as before.

In the form of the leg shown in Figure 8 there is provided an upper straight portion 37 of considerably greater length than the saddle 13, one end of this portion terminating below the saddle while the other end projects beyond the corresponding saddle end. Extending downwardly from the projecting end is a circularly arcuate ground engaging portion 38 which merges by a curve 39 into an inclined straight portion 40 from which projects a straight portion 41 parallel to the portion 37. The portion 41 is shorter than the saddle 13 and lies entirely below the saddle. The portions 37 and 38 provide the usual wide space 32.

60 In the form of leg shown in Figure 9 the bar has a straight end portion 42 engaging the saddle 13 and from one end of the portion 42 extends a downwardly inclined portion 43 which merges into one end of a circularly arcuate ground engaging portion 44. The other end of the portion 44 merges into an inclined portion 45 from which extends a portion 46 parallel to the portion 42 and terminating against the portion 43 to provide the space 32. As in the form shown in Figure 3 bolts 30 and nuts 31 hold the parts of the last three forms together, the bolts extending through the parallel portions in each form.

65 In the form shown in Figure 10 the bar is provided with a straight portion 45a which is parallel to and spaced from the saddle 13. From one end of the portion 45a extends a short and up-

wardly inclined terminal portion 46a while the other end merges into an arcuate portion 47 merging in turn into one end of an arcuate ground engaging portion 48. The other end of the portion 48 merges into the lower end of an upwardly extending and outwardly inclined portion 49 having a terminal portion 50 rebent to lie on top of the portion 46. A wide space 51, corresponding to the space 32, is formed by this construction between the portion 45 and saddle 13.

In the form shown in Figure 11 the parts are identical with those of Figure 7 except that the portion 33 is omitted and the portion 34 terminates in a reversely curved end 52 entering the notch 19. In Figure 11a the portion 34 terminates in a straight portion 53 engaging the end of the saddle 13a.

In the form shown in Figure 12 the bar has portions 54, 55, 56 and 57 corresponding closely to the like parts of Figure 10 except that the portion 57 merges directly into a portion 58 resting on the portion 55 and terminating in an upwardly bent portion 59 engaging in the notch 19. In Figure 12a this portion 59 is modified as at 60 to abut the end of the saddle 13a. Each of these forms has a wide space 51. The bolts 30a for holding the last three forms in place are slightly shorter than the bolts 30 but nuts 31 are like those previously used.

The forms of the leg shown in Figures 13 and 15 are especially adapted for production by extrusion being of generally tubular shape. In Figure 13 the shape is such that there is provided a straight portion 61 having an upstanding flange 62 at one end and from this end there extends downwardly an arcuate ground engaging portion 63 which merges through an arcuate portion 64 into the remaining end of the portion 61. These two forms may be produced from a strip by bending and welding or by cementing in the case of plastics by solvents. The flange 62 serves to hold the portion 61 spaced below the saddle to which this leg is applied. The form shown in Figure 15 is similar to that just described but a channelled portion 65 projects from the top of the flange 62 above and parallel to the portion 61. The channel 66 of this form receives the bottom of the saddle and may be milled out or formed by turning up edges of an extruded blank.

In the form shown in Figure 16 the leg consists of a substantially spherical solid member 67 which may be made of wood, rubber, metal or plastic. This member 67 is provided with a recess 68 in its bottom to receive a nut 69 and washer 70 and a bolt hole 71 extends up from this recess to receive a bolt 72 by which the parts are assembled.

In the view shown in Figure 7 the lips on the saddle block prevent the leg from turning around the bolt. The upper and lower faces of the swivel space are formed by the faces of the horizontal portions of the continuous strip forming the leg. The lower portion 36 provides a clamping face for the bolt and has its end abutting the curved portion 34 in order to solidify the formation, to prevent twisting, and also to take some of the clamping forces holding the leg to the pole.

In the view shown in Figure 8 the leg strip provides the upper face of the swivel space the same as in Figures 7 and 9, and therefore also the upper horizontal sliding bearing face for the end of the strut member of link of the spreader

bar. The lower bearing is formed by the flange of the bushing. The strip forming the leg is bent to form a sled-runner type of tread for operating conditions and lies close to the pole and to the spreader bar to prevent catching on anything when folded for carrying and storage. The horizontal bolting portion 41 of the strip has a free end with the view of simplifying production and reducing costs. In the form shown in Figure 9 there is the same relationship between the faces of the swivel space and the bearing faces for the ends of the strut members as in 8, except that the lower bearing is furnished by a separate washer instead of by the flange of the bushing. The horizontal bolting portion of the strip has an abutting end as in Figure 7.

In the form shown in Figure 10 the upper face or jaw of the swivel space is formed by the saddle block, as in Figures 6, 11 and 12. The bent strip forming the leg does not continue through to form the upper sliding bearing face for end of the strut member. Instead, both ends of the bent strip terminate adjacent the end of saddle block and at that point afford means to prevent the leg from turning on the bolt as well as means for holding the ends firmly together. The use of the saddle block to form the upper sliding bearing for the spreader bar, as shown in Figure 6, affords much greater width than the width of strip shown in Figures 5 and 4. This applies particularly when the leg is formed by a narrower strip than the relative dimensions of these figures indicate. The spacing member in Figure 10 is the same as in Figure 8, but the clamping force of the bolt is transmitted through the spacer directly against the saddle block, instead of indirectly through the end of strip forming the leg as in Figure 9. This same direct transmission of forces to saddle block and pole is shown in Figures 6, 11 and 12.

Considering now the stretcher elements and referring especially to Figures 4 to 6a inclusive and Figure 1 it will be seen that each stretcher bar includes a pair of like sections or links 73 each having an outer or leg end extremity bent to lie at a slight angle to the main or body portion of the link and adapted to enter any one of the spaces provided by the various link arrangements. In each of the forms now to be described each link has an opening 75 therein. In Figure 4 there is provided a tubular bushing 76 of such length as to fit closely between the leg portions 22 and 28. The inside diameter is such as to enable the bushing to fit properly on the bolt 30 and its outside diameter is such as to permit it to fit properly in the opening 75. As here shown the clearances between the parts have been exaggerated for the purpose of better disclosing the arrangement but it is to be understood that in any case the clearances should be such as to permit free rotation of the link 73 about the axis of the bolt 30.

In the form shown in Figure 4b the bushing is replaced by a collar 77 formed on a bolt 78 having both ends threaded to receive nuts. This form is adapted to be used with the type of leg shown in Figure 11. In each of these forms the bushing or collar affords large curved thrust bearings for the action of the strut member. The bushing and collar also act as a rigid spacer in maintaining a close sliding fit between the wide horizontal faces of the spreader link. The bushing and collar also holds these members square with each other and with the bolt as well as with the end of the spreader link and side pole.

In the form of this joint as shown in Figure 5 there is provided a bushing 79 having a peripheral flange 80 at its lower end formed integrally with the bushing. With this form the added width provided for the lower horizontally sliding faces is more effective in holding the entire pivotal connection square and in preventing the bolt from being forced out of vertical position by the eccentrically applied slanting forces of the spreader.

In the form of joint shown in Figure 6 the lower face of the saddle 13a is broadened as at 81 and a bushing 82 fits between this lower face and a separate wide washer 83 which is here shown as resting on the portion 36 of the leg shown in Figure 11. This construction affords even greater extent of horizontal sliding bearing areas than that of Figure 5 and gives maximum effect for holding the connection square and will force the spreader link to bend rather than bite into the connection.

In Figures 14, 14a and 17 to 25 inclusive are shown certain arrangements relating to the stretcher bars and in Figures 17 to 25 there are specially shown forms of connecting each pair of the links or struts 13. Each of the links has an end portion 84 extending at a slight angle to the body of the link or strut so as to lie parallel to the end 74. As shown in Figures 17, 18 and 19 there is provided a channel-like connecting link having a web 85 and parallel flanges 86 so spaced that the ends 84 may fit closely therein. Each end 84 is provided with an opening 87 and the flanges are provided with similar openings 88. In these openings is fitted a bushing 89 having on one end a flange 90 which bears against the outer face of one flange. The bushing is of proper length to extend from one outer flange face to the other. On the end of the bushing opposite the flange is a washer 91 and a bolt 92 passes through the washer 91 and bushing 89 and carries on its projecting end a nut 93.

In the joint shown in Figure 21 the connecting link is of J-shape in cross-section having a web 94, a wide flange 95 and a narrow flange 96. In this form the ends 84 are each provided with an opening 97 for the reception of a pivot member having a body 98 provided with a flange 99 at one end and a reduced and threaded end 100 at the other. The reduced and threaded end 100 extends through an opening 101 in the flange 95 and on this end is fitted a washer 102 and nut 103 by means of which the pivot bolt is fixed firmly in position. The length of the body 98 is such that the washer and flange 95 form flat bearings for the end 84.

In the form of this connection shown in Figures 22 and 23 the connecting link is a flat bar 104 and on one side at each end there is mounted a stop member 105 firmly fixed in place by a rivet 106. Each member 105 has a lip 107 projecting over the bar 104 towards the side opposite that on which the member 105 is fixed. The strut or link end 84 is provided with an opening wherein is fitted a bushing 109 and for each end 84 the bar 104 is provided with an opening 110. A bolt 111 extends through the bushing and has a flange-like head 112 which bears against one end of the bushing 108 while the other end of said bushing rests against the bar 104. The bolt is provided with a washer 113 and nut 114 by which the parts are rigidly assembled.

In the form of joint shown in Figures 24 and 25 the connecting link is formed by a pair of spaced parallel plates 115. Adjacent one side

edge these plates are secured by connecting posts 116 which also form stop members. At the center of the other side edge the plates are connected by a post 117 carrying a yoke member 118 which lies between the links 13 when the litter is collapsed. The ends 84 are held between these plates by any suitable pivot means indicated at 119.

In Figures 14 and 14a is shown means whereby the effective lengths of the struts or links 13 may be increased in case the fabric becomes loose between the poles as may happen by stretching of the fabric after considerable use. To accomplish this one end of each link is provided with an elongated opening 120 wherein is fitted a lunate bushing 121 the normal position of which is shown in full lines in Figure 4 and the position for adjusting to greater length between pivot points of the strut in dotted lines. Obviously, the arrangement just described may be used at either end of each link. If used at the junction of two links a pivot such as the bushing 89 or bolt 92 is received in the opening 120 between the member 121 and the opposite end of the opening while, if the arrangement is at the junction of the link and leg a bushing such as 76 lies similarly in the opening 120.

The exact stopping points of the spreader bar in its travel over dead center is determined by the distance of the holes in the connecting link from the inside face of the web portion, and by the length of this interposed stop and reenforcing member. Figure 17 shows this stop member in the fully folded position of the spreader bar, where the ends of the strut members engage the web at sufficiently separated points to prevent a pendulum swing of the entire spreader bar assembly when the litter is fully folded for carrying or for storage.

As a reenforcement to the spreader bar, this interposed member strengthens its jointed mid-length portion in the direction of its tendency to buckle, which is transverse to its horizontal plane of operation. In spreader bar construction, it is necessary for the operating plane of the mid-length portion of the spreader bar to lie substantially below the operating plane of its connections of the side poles. This is shown in Figure 2 and in the angle of the ends of the strut members in various other figures. This is to afford ample clearance for a heavy person to sink into the tightly stretched canvas, and also to allow for the canvas becoming permanently stretched with extended use. The adjustable-length feature of strut member eliminates the necessity for this allowance for permanent stretch of canvas. It follows then, that the spreader bar can be designed and constructed with less concavity or drop which means less distance between the above mentioned operating planes and less normal buckling tendency to contend with in the spreader bar design. The interposed reenforcing member enables these reductions to be carried still further and consequently further reduces the cross-strains which must be absorbed by the spreader bar in the normal setting up and tightening of the canvas, and which still further must be absorbed when the slanting strut members tend to buckle the spreader bar to a still deeper conformation as the litter canvas is loaded with a very heavy person. Reenforcement against this downward buckling is effectively accomplished by an interposed member along the mid-length portion of the spreader bar where the buckling cross-strains are the greatest and

where holes for the pivoting connections weaken the section of the strut members. The section and design of this interposed reenforcing member may be such as to add any desired resistance found necessary in the mid-length jointed portion of the spreader bar to resist buckling, thus obviating the need for putting this extra strength and weight into the full length of the strut members. The extra rigidity of the reenforcing member greatly reduces the lever arm tending to buckle the remaining portion of the length of strut members lying beyond the ends of said member, thus enabling all parts to be made lighter, and subject to less binding and cross-strains in all pivoting bearings. With the concavity allowance in the spreader bar eliminated by strut member adjustment, and with less concavity required on account of mid-length reinforcement of spreader bar and consequent less deflection, all parts of the mechanism are made lighter, the legs lower with less material, and the folded litter as a package has smaller dimensions.

The open end swivelling space in the leg, as shown in Figure 3, allows the straight-end strut member to swing almost completely under the side pole, thus permitting the litter to be folded laterally into the smallest practicable space. No portion of the mechanism interferes to limit the fully closed width, the bulk of folded canvas lying between the poles being the only factor that prevents the poles from coming solidly together. A fully closed width of five inches is easily attained. When curved strut members or goose-neck and offset ends are used to attain side-entrance access to the bolt around a semi-obstructing portion of the leg, or when swivel blocks are used or projections extend inwardly from leg to afford a round-about connection for the spreader bar, the interference of these parts with each other is the determining factor in obtaining minimum folding dimensions.

In the form shown in Figures 13 the leg 14 is extruded in the same manner as that in which pipes are extruded, the part 62 corresponding to a flange or rib on an ordinary pipe. The extrusion of the form shown in Figure 15 is accomplished in a similar manner, the formation of the channel 66 being accomplished by appropriate machining as, for instance, by means of a milling machine.

What is claimed as new, is:

1. In a folding litter having fabric connected side poles, stretcher bars, and pole saddles under each side pole; separate supporting legs each located beneath a respective saddle with its longitudinal dimension extending along the pole and arranged to provide a low and wide space extending transversely of the pole and open at both sides and at one end beneath said pole for the reception of an end of a stretcher bar, each of said legs including a horizontal upper portion spaced below the saddle, a ground engaging portion, means connecting the horizontal and ground engaging portions, means holding the horizontal portion in spaced relation to the saddle, and means engaging the respective saddle, each saddle having means coacting with the saddle engaging means of the respective leg and restraining the leg from rotation on its saddle, and means to connect the stretcher bar pivotally to the saddle in said space.

2. In a folding litter having fabric connected side poles, stretcher bars, and pole saddles under each side pole; separate supporting legs each located beneath a respective saddle with its lon-

gitudinal dimension extending along the pole and arranged to provide a low and wide space extending transversely of the pole and open at both sides and at one end beneath said pole for the reception of an end of a stretcher bar, each of said legs including a horizontal upper portion spaced below the saddle, a ground engaging portion, means connecting the horizontal and ground engaging portions, means holding the horizontal portion in spaced relation to the saddle, and means engaging the respective saddle, each saddle having means coacting with the saddle engaging means of the respective leg and restraining the leg from rotation on its saddle, and means to connect the stretcher bar pivotally to the saddle in said space, said means being so arranged and positioned as to permit the major portions of the stretcher bars to lie beneath the poles upon collapse of the litter.

3. In a folding litter having fabric connected side poles, stretcher bars, and pole saddles under each side pole; separate supporting legs each located beneath a respective saddle with its longitudinal dimension extending along the pole and arranged to provide a low and wide space extending transversely of the pole and open at both sides and at one end beneath said pole for the reception of an end of a stretcher bar, each of said legs including a horizontal upper portion spaced below the saddle, a ground engaging portion, means connecting the horizontal and ground engaging portions, means holding the horizontal portion in spaced relation to the saddle, and means engaging the respective saddle, each saddle having means coacting with the saddle engaging means of the respective leg and restraining the leg from rotation on its saddle, and means to connect the stretcher bar pivotally to the saddle in said space, said means being so arranged and positioned as to permit the major portions of the stretcher bars to lie beneath the poles upon collapse of the litter.

4. In a folding litter having fabric connected side poles, jointed stretcher bars, having end portions forming struts and pole saddles under each side pole; separate supporting legs each located beneath a respective saddle with its longitudinal dimension extending longitudinally of the pole and arranged to provide a low and wide space open at each side of the pole, one end of said space being open and the other closed, each of said legs including a horizontal upper portion spaced below the saddle, a ground engaging portion, means connecting the horizontal and ground engaging portions, means holding the horizontal portion in spaced relation to the saddle, and means engaging the respective saddle, each saddle having means coacting with the saddle engaging means of the respective leg and restraining the leg from rotation on its saddle, each strut portion of a stretcher bar having an end fitting closely between the top and bottom walls of said space, a bolt extending vertically through the pole and strut end and securing the leg and saddle to the pole and connecting the strut pivotally thereto, and spacer means associated with said bolt and bearing at its ends against the top and bottom walls of said space.

5. In a folding litter having fabric connected side poles, jointed stretcher bars, having end portions forming struts and pole saddles under each side pole; separate supporting legs each located beneath a respective saddle with its lon-

longitudinal dimension extending longitudinally of the pole and arranged to provide a low and wide space open at each side of the pole, one end of said space being open and the other closed, each of said legs including a horizontal upper portion spaced below the saddle, a ground engaging portion, means connecting the horizontal and ground engaging portions, means holding the horizontal portion in spaced relation to the saddle, and means engaging the respective saddle, each saddle having means coacting with the saddle engaging means of the respective leg and restraining the leg from rotation on its saddle, each strut portion of a stretcher bar having an end fitting closely between the top and bottom walls of said space, a bolt extending vertically through the pole and strut end and securing the leg and saddle to the pole and connecting the strut pivotally thereto, and spacer means associated with said bolt and bearing at its ends against the top and bottom walls of said space, said spacer means maintaining the said walls in proper spaced relation whereby to maintain a sliding fit between the said walls and strut, to prevent said walls being drawn together by the clamping action of said bolt and to prevent the lateral portions of the strut from being forced into the walls of said space during pivotal action of the strut.

6. In a folding litter having fabric connected side poles, stretcher bars, and pole saddles under each side pole; separate legs each associated with a saddle and consisting of a length of bar metal of uniform cross section and bent to provide an arcuate ground engaging portion, a horizontal portion and a portion engaging a saddle and holding the horizontal portion in spaced parallel relation to the under side of the saddle to provide a space for the end of a stretcher bar, said saddle being provided with means coacting with the portion of the leg engaging the saddle and acting to prevent rotation of the leg on the saddle, and a bolt passing through the pole, the saddle and said horizontal portion and forming a pivot for the stretcher bar and connecting means for the leg and saddle.

7. In a folding litter having fabric connected side poles, stretcher bars, and pole saddles under each side pole; separate legs each associated with a saddle and consisting of a length of bar metal of uniform cross section and bent to provide an arcuate ground engaging portion, a horizontal portion and a portion engaging a saddle and holding the horizontal portion in spaced parallel relation to the under side of the saddle to provide a space for the end of a stretcher bar, a bolt passing through the pole, the saddle and said horizontal portion and forming a pivot for the stretcher bar and connecting means for the leg and saddle, a cylindrical spacer element surrounding said bolt and engaging the top and bottom walls of said space, said stretcher bar having an opening therein fitting said spacer element, and interlocking coacting means on the saddle and leg holding the leg against rotation with respect to the saddle on said bolt.

8. In a folding litter having fabric connected side poles, stretcher bars, and pole saddles under each side pole; separate legs each associated with a saddle and consisting of a length of bar metal of uniform cross-sectional dimension bent to provide an arcuate ground engaging portion, a lower horizontal portion and an upper horizontal portion spaced above the lower horizontal portion to provide a stretcher bar end receiving

space, said upper horizontal portion engaging the bottom of a saddle, said saddle having a channel on its under side receiving said upper horizontal portion, and a bolt passing through the pole, the saddle and said horizontal portions to hold the leg, saddle and pole together and to constitute a pivot for the stretcher bar.

9. In a folding litter having fabric connected side poles, stretcher bars, and pole saddles under each side pole; separate legs each associated with a saddle and consisting of a length of bar metal of uniform cross-sectional dimension bent to provide an arcuate ground engaging portion, a lower horizontal portion and an upper horizontal portion spaced above the lower horizontal portion to provide a stretcher bar end receiving space, said upper horizontal portion engaging the bottom of a saddle, a bolt passing through the pole, the saddle and said horizontal portions to hold the leg, saddle, the stretcher bar end and pole together and to constitute a pivot for the stretcher bar, and a cylindrical spacer element surrounding said bolt and engaging the top and bottom walls of said space, said stretcher bar having an opening therein fitting said spacer element.

10. In a folding litter having fabric connected side poles, stretcher bars, and pole saddles under each side pole; separate legs each associated with a saddle and consisting of a length of bar metal of uniform cross-sectional dimension bent to provide an arcuate ground engaging portion, a lower horizontal portion and an upper horizontal portion spaced above the lower horizontal portion to provide a stretcher bar end receiving space, said upper horizontal portion engaging the bottom of a saddle, a bolt passing through the pole, the saddle and said horizontal portions to hold the leg, saddle and pole together and to constitute a pivot for the stretcher bar, and a cylindrical spacer element surrounding said bolt and engaging the top and bottom walls of said space, said stretcher bar having an opening therein fitting said spacer element, and means on said saddle engaging the sides of the upper horizontal portion of the leg and holding the latter against rotation on the bolt with respect to said saddle.

11. In a folding litter having side poles connected by flexible material and legs secured beneath said poles; stretcher bar constructions connecting the legs of one pole with the legs of the other and each including a pair of struts and means pivotally connecting adjacent ends of said struts, the remote ends of said struts being pivotally connected to said legs, each of said struts having a pivot receiving hole adjacent each end, at least one hole of each strut being elongated in the direction of the length of the strut, and an insert for each elongated hole formed to fit a selected end of the hole to leave a cylindrical pivot receiving space between the insert and the opposite end of the hole.

12. In a folding litter, a leg member consisting of a single length of strap material having a portion extending from one end provided with a part extending horizontally to fit against a pole saddle and having a part inclined downwardly from the first part away from said end, said strap material having a second portion extending from the other end below and parallel to said first part, the extremity of the last mentioned portion engaging the under side of the first portion and holding said second portion from upward movement, said leg having a ground engaging portion and side portions connecting

the ends of the ground engaging portion to said first and second portions.

13. In a folding litter, a leg member consisting of a single length of strap material having an end portion adapted to fit against a pole saddle, said member having a portion below the first portion and provided with an end engaging the

first portion and holding the second portion against upward movement, said leg having a ground engaging portion and side portions connecting the ends of the ground engaging portion respectively to said first and second portions.

SAMUEL G. THOMSON.
